(57) **CLAIM**

The ornamental design for a power supply device for electronic atomizer, as shown and described.

DESCRIPTION

FIG. 1 is a perspective view of a power supply device for electronic atomizer of our design;

FIG. 2 is another perspective view thereof;

FIG. 3 is a front elevational view thereof;

FIG. 4 is a rear side elevational view thereof;

FIG. 5 is a left side elevational view thereof;

FIG. 6 is a right side elevational view thereof;

FIG. 7 is an enlarged top plan view thereof;

FIG. 8 is an enlarged bottom plan view thereof;

FIG. 9 is an enlarged view of area 9 circumscribed in FIG. 1; and,

FIG. 10 is an enlarged view of area 10 circumscribed in FIG. 2.

The broken lines consisting of evenly space dash lines in the drawing depict parts of the power supply device for electronic atomizer that form no part of the claimed design.

The long dash-short dash broken lines in the drawings depict the boundaries of the enlarged views and form no part of the claimed design.
